UNITED STATES PATENT OFFICE.

FRANK HARTLEY, OF SHIPLEY, AND THOMAS KELLEY, OF BRADFORD, ENGLAND.

BUR-CRUSHING MECHANISM.

1,367,700.

Specification of Letters Patent.

Patented Feb. 8, 1921.

Application filed June 25, 1919. Serial No. 306,705.

To all whom it may concern:

Be it known that we, FRANK HARTLEY and THOMAS KELLEY, subjects of the King of Great Britain, residing at Shipley and Bradford, both in the county of Yorkshire and Kingdom of England, respectively, have invented certain new and useful Improvements in Bur-Crushing Mechanism, of which the following is a specification.

10 This invention has reference to calendering machines, bur crushers and other apparatus where the material to be treated is drawn between a pair of rollers for the purpose of smoothing it, or for crushing the 15 burs or other foreign matter contained therein, and so on. The said invention has been designed more especially for use in connection with wool carding and analogous machines for crushing burs or other impurities in a sheet or sliver, wherein a weighted 20 top roller is capable of being moved into and out of contact with a bottom roller, but it is applicable for other purposes as above indicated.

25 Prior to this invention, it has been proposed to mount at each end of the apparatus and in contact with the bearings of the upper roller a cam member for raising the upper roller out of contact with the lower 30 one, or for lowering the same into contact therewith. Such cams comprise squared spindles mounted so as to extend longitudinally of the bearings and each cam was operated by means of a lever, the levers being 35 in turn connected by a rod so that the cams were operated together by pulling the rod forwardly and rearwardly. The weighted top roller was driven from the lower one by toothed wheels the teeth of which were 40 made deep so that they were not moved out of mesh. In our experience we have found that great force had to be applied to the rod in order to turn these squared cam spindles which extended the full length of each bearing, because of the surface friction to be 45 overcome in order to lift the weighted top roller. In fact it was proposed to turn the said squared cam spindles by means of a worm gear so as to give a more powerful 50 effect with a diminished rate of motion.

Furthermore, we have in our experience not found the deep toothed wheels run smoothly; in fact, in order to try and make them run more smoothly it was proposed to inclose 55 them in an oil tight case so as to revolve in an oil bath.

Our present invention is designed to avoid the use of these squared cam spindles and to substitute therefor a device which will require less power to operate it; also to dispense with the deep toothed wheels and substitute therefor, a driving gear which will run more smoothly.

Our improvement is characterized in that spindles circular in cross section are mounted 60 at each end of the apparatus and in contact with the bearings of the upper roller, a rounded stud or ball being provided on each spindle, and a corresponding depression on the under side of the bearings so arranged 65 that turning of the spindles will raise the upper roller when the rounded projection impacts against the underside of the bearings, and also snap into the depression so as to prevent accidental disengagement. A 70 further feature of our invention is that the upper roller is driven from the lower one by a chain drive, the chain being passed 75 from chain wheels on the roller spindles to a tightening jockey sprocket wheel or wheels. 80 We are aware that it has been proposed to provide wringing and mangling machines with chain drives having a chain tightening wheel; but such drives have not been used 85 so far as we are aware in connection with bur crushers.

The invention will be understood from the following description reference being had to the accompanying drawings, in which:—

90 Figure 1 is an end elevation and Fig. 2 is a side elevation of an apparatus constructed according to our invention, as applied to the delivery end of a carding engine;

Figs. 3 and 4 are detail views in end and 95 side elevation.

Fig. 5 is a detail view of the bracket 19 shown in Fig. 2,

Fig. 6 is a side elevation of a portion of 100 a carding engine showing our apparatus applied between the doffer and the angle strippers instead of at the delivery end of the carding engine.

In carrying the invention into effect, the upper and lower rollers 1 and 2 are journaled in bearings or bushes which are located in upstanding supports 3 on the main frame 4 of the machine in such a way that the bearings or bushes for the upper roller are capable of a certain amount of perpendicular movement. The upper roller 1 is 105 driven from the lower roller 2 by means of

a chain and sprocket gear, there being a sprocket wheel 5 secured to the upper roller 1, a sprocket wheel 6 secured to the shaft of the lower roller 2, and two jockey or idle sprocket wheels 7 one at each side of the latter, one or both of which are adjustable to vary the tension of the driving chain 8. The driving chain 8 is passed over the sprocket wheel 5 of the upper roller, under the jockey sprocket wheels 7, and over the sprocket wheel 6 which is secured to the shaft of the lower roller, and this chain transmits a positive drive in the right direction to the upper roller 1. A suitable amount of slack is left in the chain to allow the upper roller 1 to be lifted, this slack being adjustable by the jockey sprocket wheels 7 as aforesaid, so that there is no danger of the chain and sprocket wheels coming out of mesh as 20 would be the case with toothed gear.

Journalized in each of the two upstanding supports 3 is a transverse spindle 9 to which is affixed a disk or boss 10 having a rounded stud 11 or ball projecting therefrom, and the front end of each spindle is provided with a lever 12 by which such spindles 9 can be turned. The said disks are located immediately under the bearings or bushes 13 in which the upper roller 1 is journalized, so that by turning the levers 12 in one direction the studs 11 impact against the underside of the bearings or bushes 13 and lift the upper roller 1, or by turning the levers 12 in the other direction the upper-roller 1 descends by its own weight or the weights 14 by which it is loaded. These rounded studs or balls 11 prevent the least possible surface friction, so that only a very moderate amount of force has to be expended to 40 lift the roller. Those parts of the bearings or bushes 13 against which the studs 11 impact are formed with V shaped or other suitably shaped recesses 15 so that points of the studs 11 will snap thereinto and so prevent 45 accidental disengagement. The two levers 12 may be operated separately if desired, first one and then the other, or the said two levers may be connected together by a hand bar 16 so that both ends of the upper roller 1 may be operated simultaneously. This hand bar is to the front of but below the rollers. The chain and sprocket gear may be covered by an oil tight case or guard. 17 is a handle by which the lifting and lowering of the roll 1 is effected, simultaneously at each end. The dotted lines show the position that the parts assume when the upper roller 1 is in the raised position. The jockey sprocket wheels are mounted freely on 50 headed stub spindles 18 secured by nuts to a bracket 19 bolted to the frame 4 of the machine, and one ear of the bracket in which one of the stud spindles is mounted is slotted to allow for adjustment to tighten or 60 loosen the chain as shown.

In Fig. 6 in which the apparatus is applied between the doffer and the angle strippers, 20 are the upper rollers (in this case there are two) whose shafts are journaled in bearings 21 capable of moving in 70 guides 22, and 23 is the lower roller journaled in bearings 24. The upper rollers 20 are driven from the lower roller 23 by means of a chain and sprocket gear, there being a sprocket wheel 25 secured to each upper 75 roller, a sprocket wheel 26 secured to the lower roller, and a jockey sprocket wheel 27 which is adjustable. The driving chain 28 is passed over the sprocket wheels 25, under the jockey wheel 27 and over the sprocket 80 wheel 26 and this chain transmits a positive drive in the right direction to the upper rollers. Journaled in supports is a spindle 29 in which are two small recesses 30, while the underside of the bearings 21 are provided with rounded studs or balls which enter these recesses. The spindle is provided with a hand wheel 31 by which it can be turned. The turning of this hand wheel in one direction causes the recesses 30 to be 85 moved clear of the studs, thus lifting the upper rollers 20, or by turning the hand wheel 31 in the other direction, the studs drop back into the recesses thus lowering the upper rollers 20 relative to the lower one 23. 90 32 is the doffer, 33 the doffing knife, 34 the angle stripper, 35 the stripper and 36 elevator.

The advantages and operation of this improved appliance will now be apparent. It 100 is to be understood however that we do not consider ourselves limited to the precise details of construction herein described, as changes could be readily suggested which would not involve a departure from the 105 scope of the invention herein set forth. For instance the studs 11 could be made to project from the spindles 9 themselves instead of from disks or bosses secured to the spindles, or instead of studs, cams or ball bearings might be used. It must therefore be understood that the foregoing description shall be interpreted as illustrative, and not 110 in a limiting sense.

We declare that what we claim is:

1. In apparatus for crushing burs in wool or for like purposes, wherein the material under treatment is passed between rollers, the combination with the upper weighted roller or rollers, of spindles located beneath 120 the bearings thereof, and rounded studs or balls provided on said spindles which serve to raise or lower said upper roller or rollers on the turning of said spindles without necessitating the removal of the weights. 125

2. In apparatus for crushing burs in wool or for other like purposes, wherein the material under treatment is passed between rollers, the combination with the upper weighted roller or rollers, of spindles lo- 130

cated beneath the bearings thereof, rounded studs or balls provided on said spindles which serve to raise or lower said upper roller or rollers on the turning of said spindles without necessitating the removal of the weights, and recesses on the under side of the bearings into which the rounded studs or balls are adapted to snap to prevent accidental disengagement of the parts.

10 3. In apparatus for crushing burs of wool, or for like purposes, wherein the material under treatment is passed between rollers, the combination with the underside of the upper weighted roller or rollers, of spindles located beneath the bearings thereof and provided with recesses, and rounded studs or balls on the under side of the bearings adapted to engage said recesses so that the turning of the spindles in one direction 15 causes the recesses to be moved clear of the studs, and thereby lift the rollers.

15 4. In apparatus for crushing burs in wool

or for like purposes, wherein the material under treatment is passed between rollers, means for raising or lowering the upper 25 roller relative to the lower one, and gear for driving the upper roller from the lower one and so arranged as to prevent the rollers coming out of gear, such gear comprising sprocket wheels secured to the roller shafts, 30 a jockey pulley or pulleys mounted on said stud spindles capable of adjustment, and a driving chain passing around said sprocket wheels.

In witness whereof we have hereunto 35 signed our names this fourth day of June, 1919, in the presence of two subscribing witnesses.

FRANK HARTLEY.
THOMAS KELLEY.
